UNITED STATES PATENT OFFICE.

FREDERICK G. SARGENT, OF WESTFORD, MASSACHUSETTS.

WOOL-WASHING MACHINE.

SPECIFICATION forming part of Letters Patent No. 223,393, dated January 6, 1880.

Application filed October 19, 1877.

To all whom it may concern:

Be it known that I, FREDERICK G. SARGENT, of Westford, in the county of Middlesex and State of Massachusetts, have invented 5 certain new and useful Improvements in Wool-Washing Machines, of which the following is a description.

The object of my invention is to provide a wool-washing machine which shall operate 10 evenly, smoothly, and uniformly.

The nature of the invention will fully appear from the subjoined description, when considered with reference to the accompanying drawings, forming part of this specification.

15 In the accompanying drawings, in which similar letters of reference indicate like parts, Figure 1 is a longitudinal section. Fig. 2 shows the carrier.

20 A is the bowl of the machine. B is the inclined table; C, the rake. E is the carrier. F is a cross-bar reaching from one side of the bowl to the other, and placed between the rake and carrier in such position as not to be within the path of either. To this cross-bar are attached fingers G, made of wire or other suitable material. From the bar they are carried backward, gradually nearing the table, and when near thereto carried along parallel therewith for a considerable distance toward the squeeze- 25 rolls between the rows of teeth upon the carrier. D is the crank which moves the fork C, whose arm or staff C' slides in the pivoted sleeve e. L is one of the rock-shaft arms, which is connected with the one upon the other 30 end of the rock-shaft at its top by a rod, upon which the rear end of the carrier E is supported. H is a central support for the cranks D and K. J is a rigid arm attached to the carrier E and provided with the hook a, which 35 rests upon the pin of crank K.

40 The relative position of the shaft of crank K, the inclined table B, rock-shaft arms L, carrier E, and arm J is such that the carrier will be moved a greater distance on a line substantially parallel with the table than it is upon a line perpendicular to it, while it is constantly supported and moved by the crank, thus obviating the shocks and strains which a machine giving to its carrier an intermittent 45 motion is subjected to.

50 The bar F, being placed above the fluid-

level in the bowl A, will have the wool crowded under it by the fork C, and as the fingers G begin at the bar F they will rest upon the wool and press it down upon the table B; and as they are constructed of some flexible material they will serve to prevent the wool being thrown in large masses upon the table, where the first movement of the carrier will catch and carry it forward toward the squeeze-rolls 55 so quickly that it will not be evened out and spread as much as is desirable to secure the most perfect operation of the rollers upon it. When the wool is crowded under the fingers 60 the carrier E, dropping its teeth between them near the bar F, moves forward, carrying the wool upon the table toward the squeeze-rolls; but the fingers, pressing down upon it with a pressure increasing in proportion to the bulk 65 beneath them, besides keeping back the larger 70 bunches, so the teeth of the carrier will not catch into their greatest mass, serve to hold the wool back sufficiently to greatly even out any bunches which the fork C may deliver under the bar F, and as the fork C always delivers the wool to the carrier E in an irregular 75 manner, sometimes making a movement without delivering any and sometimes delivering twice as much as should be allowed to go upon the table at once, my device, by holding back 80 such large masses, permits the carrier to be continuously operating upon the fiber. In evening the sheet it moves forward to the squeeze-rolls, which therefore discharge the wool more evenly and thoroughly squeezed 85 and dried. The fingers G also serve the purpose of holding the wool wherever the carrier leaves it to make its return stroke, and thus avoid the use of teeth projecting upward from the table over which the wool must be dragged 90 as it passes toward the rolls; and as I construct the table of perforated metal the wool continues to drain as it passes up toward the roll while so held by the fingers, without having its liquor run back upon the wool lower down 95 upon the table. One portion of the table I make removable, so that the part of the tank below it is more readily reached for examination or cleansing.

By constructing the crank K, bar J, and 100 carrier E of the proper relative proportions, any desired backward and forward movement

of the carrier can be obtained with a much smaller movement toward and from the table, and I am enabled, therefore, to obtain the proper and necessary movement for the carrier 5 while directly connected with its driving crank, and without the use of guide and slide rods or intermittent devices for moving the carrier.

By the above-described construction I am 10 enabled to produce a wool-washing machine which operates with less jar, more evenly, and which requires less power and less parts than rake-and-carrier machines as heretofore made.

What I claim as new and of my invention 15 is—

1. In combination with the table B and carrier E, the finger G, attached to the bar F at the rake end of the machine, substantially as described.

2. The combination of the carrier E, having the rigid arm J, with the crank K, the outer end of the arm resting directly on the pin of the crank, substantially as described. ²⁰

FREDERICK G. SARGENT.
